UNITED STATES PATENT OFFICE

EDGAR LEE HAWLEY, OF ATLANTA, GEORGIA

SECONDARY CONTACT SPRING FOR PLUG CUT-OUTS

Application filed July 6, 1929. Serial No. 376,449.

This invention relates to plug cut-outs, and has as its primary object the provision of an improved secondary contact spring for such plug cut-outs.

5 The principal object of this device is the provision of an improved secondary contact spring for plug cut-outs, which will prevent the completion of an electrical circuit between the plug and the contacts of 10 the plug cut-out through the medium of a coin or other like copper insertion disposed between the fuse plug contact and the base contact so that a complete circuit will be closed between the fuse plug contact and 15 the other contact member located within the cut-out for completing a circuit.

Other objects and advantages of this invention will become apparent during a study of the following description, taken in conjunction with the accompanying drawings, 20 wherein:

Figure 1 is a view partly in section and partly in elevation of a cut-out for fuse and showing the application of my improved 25 secondary contact spring therewith.

Figure 2 is a front elevation of the cut-out with the fuse removed.

Figure 3 is a perspective view of my improved secondary spring contact.

30 Figure 4 is a rear elevation of the socket for receiving the fuse plug.

With reference more in detail to the drawings, it will be seen that my improved cut-out designated generally by the reference 35 character A consists of a substantially rectangular base block designated generally by the reference character 5, and it is to be understood that this block 5 may be made of porcelain or any other suitable material. This block 5 is provided with a substantially rectangular recess 6 extending inwardly from one face of the block as clearly suggested in Figure 1.

To cover the recess 6 I provide a substantially rectangular shaped plate 7 of bakelite or any other suitable composition, or if desired, metal, the material forming this plate being left to the desire of the manufacturer. This plate 7 which may be termed 50 the cover plate is provided with a circular

opening 8 formed therein and communicating with the recess 6 formed in the block. Located within the recess 6 of the block 5 adjacent the upper end of the recess there is provided a stationary contact member 9, this 55 contact member being suitably fixed to the rear wall of the recess 6, and the outer face of the contact member is substantially concave as suggested in Figure 1.

My invention per se consists of a secondary 60 contact member which consists of an elongated flexible spring steel strip 10, which spring 10 at its lower end is offset laterally, said offset portion being curved outwardly as suggested at 11. This outwardly curved 65 offset portion 11 of the spring 10 is apertured as at 12, and the curved offset portion 11 is suitably received in a recess or otherwise imbedded in the inner face of the cover plate 7 adjacent the lower end of the cover plate and 70 a bolt 13 extends through the cover plate 7 and the aperture in the offset 11 and lock nut 14 is threadedly engaged on the inner end of the bolt 13 and bears against this offset 11 for maintaining the same in the recess of the 75 plate 7.

At its upper end the spring 10 is provided with a contact member 15, which contact member has a rounded face 16, said contact member 15 being complementary to the stationary contact member 9 as suggested in Figure 1. As shown, the contact member 15 extends laterally from the upper end of the spring 10 from the inner face of the spring, while intermediate the ends of the spring 10 the same 80 has formed thereon and extending or disposed on the opposite face thereof a substantially disc-like contact member 17.

This disc-like contact member 17 has its inner face bevelled as suggested as at 18 and is provided on the bevelled face with an extension 19 which extends through the spring 10 to project laterally from the opposite face of the spring and in the same direction as the contact member 15. 20 represents a flexible 90 conductor which is electrically connected with the contact 17 through the medium of the extension 19 of the contact and at its opposite end is electrically connected with the contact member 15. This flexible conductor 95 100

as shown is preferably crimped. The contact member 17 is located on the spring 10 on that portion of the spring opposite the opening 8 formed in the cover plate 7 so that under 5 normal conditions and due to the flexibility of the spring and its offset 11, the spring will be urged inwardly toward the inner face of the plate 7 thus permitting the said contact member 17 to extend within the opening 8.

10 Secured to the outer face of the cover plate 7 is a suitable fuse socket 21 and this fuse socket 21 is of the ordinary socket construction, with the exception that the socket is open at both its front and rear and extending 15 radially from the socket adjacent its open ends the same has a plurality of spaced ears 22, which ears 22 are apertured and extend from diametrically opposite sides of the socket, to constitute attaching ears, while the 20 third ear 23 is bent downwardly upon itself as suggested in Figure 1 and constitutes a connector for an electrical conductor.

Suitable screws 22' are received through the apertures in the attaching ears 22 to be screw 25 threadedly engaged with the plate 7 as suggested in Figure 2. A screw 24, has the head thereof imbedded in the cover plate 7 and the shank thereof extending laterally from the cover plate and through the apertures in the 30 ear 23 and a nut is threaded on the outer end of the screw so that an electrical conductor wire may be held within the space between the body of the ear and its downwardly bent portion.

35 A conductor 26 is connected at one end with the stationary contact 9 as at 27, and at its opposite end extends through that portion of the block constituting the bottom wall of the recess 6, as shown. A substantially U-shaped 40 connector clip 28 is disposed within a suitable recess 29 formed on the outer face of the block 5 adjacent the lower end of the block, and a screw 30 passes through the upper portions of the legs of the U-shaped connector 28 and 45 through the lower end of the conductor member 26 for screw-threaded engagement with an internally threaded socket of a suitable block 31 imbedded in the block 5 and extending inwardly from the rear face of the block.

50 When a fuse 34 is properly screwed into the fuse socket 21, the protruding contact 34 of the fuse will engage the contact 17 of the spring 10 and force the latter inwardly to dispose the contact 15 in engagement with the 55 stationary contact 9 of the conductor 26. The circuit will thus be completed between the connectors 23 and 28 in an obvious manner.

As is well known to complete a circuit between the contact of the fuse plug 33 and 60 the base contact 17 it has often been the practice to insert a coin such as a penny between said contacts which of course results in the backing or short-circuiting of plug cut-outs, this usually being done by some layman in 65 order to obtain light after an overloaded

70 fuse is blown and not realizing that he is doing away with the protection provided for the fuse, usually forgetting to remove the penny, and replace with a good fuse. In so doing, he is of course subjecting his property to the risk of fire when other trouble may arise in the circuit.

75 However, by my construction the completion of the circuit through the intermediacy of a penny or like copper disc is prohibited since obviously, in the contemplated form of the invention and in actual practice the opening 8 is of a diameter as to prevent the insertion of a penny within the opening, the diameter of the opening being intended to be such as to only accommodate the protruding contacts of the fuse 33. Likewise the base contact 17 carried by the spring 10 may be of a size merely enabling contact thereof with the contact member of the fuse plug.

80 Obviously then, if a penny be inserted between the first contact 17 and the contact member of the fuse plug 33, a circuit would be completed between the plug and the base contact 17, but since the penny is not permitted to be pushed through the opening 8, the movable contact 15 carried by the spring 10 may be maintained out of electrical connection with the stationary contact 9 since no pressure is exerted upon the spring forcing the same inwardly so that the last mentioned contacts may engage one with another for completing the circuit.

85 From the foregoing, it will be seen that I have provided a thoroughly reliable and practical secondary spring contact for fuse 90 plug cut-outs and that the same is positive in operation, simple in construction, inexpensive to manufacture, and otherwise well adapted for the purpose desired.

95 Even though I have herein shown and described the preferred embodiment of my invention, it is to be understood that the same is susceptible to changes fully comprehended by the same and by the scope of the appended 100 claim.

Having thus described my invention, what I wish to claim as new is:

105 A plug cut out comprising a fuse box having a recess and a fixed contact in the recess, a cover for said recess having a substantially small central aperture, a flat spring disposed upon the inner face of said cover and extending diametrically of the central aperture, said spring having one end secured to the cover and being flexed to normally lie flat against the cover, a pair of contacts mounted on said spring and extending oppositely therefrom, one of said contacts being 115 positioned adjacent the free terminal of the spring for engagement with the fixed contact of the recess when the spring is flexed outwardly from the cover, and the other contact being positioned intermediate the ends of the spring and normally extending through the 120

aperture of the cover for engagement with
a fuse, a flexible conductor electrically con-
necting the said contact of the spring, a fuse
socket mounted on the outer face of said cover
and over the central aperture thereof, said
5 socket having its bottom end open to expose
the said aperture and said fuse-contact mem-
ber of the spring, and a connector on said
socket for an electrical conductor.

10 In testimony whereof I affix my signature.
EDGAR L. HAWLEY.
